W. I. STINE

WINDOW ANTIRATTLER

Filed Dec. 27, 1923

FIG. 1

By

N. E. Gee.

Attorney

Inventor

W. I. STINE

UNITED STATES PATENT OFFICE.

WILLIAM I. STINE, OF ALTOONA, PENNSYLVANIA.

WINDOW ANTIRATTLER.

Application filed December 27, 1923. Serial No. 683,026.

To all whom it may concern:

Be it known that WILLIAM I. STINE, a citizen of the United States, residing at Altoona, in the county of Blair and State of Pennsylvania, has invented certain new and useful Improvements in Window Antirattlers, of which the following is a specification.

This invention relates to windows and window casings and has for its primary object an improved device that is adapted to be placed between the window sash and sash casing to prevent the usual rattling noise which is quite pronounced in loosely fitted window sash.

Another object of this invention is to provide a window sash antirattler that is not adapted to be attached to the window sash as is the usual custom, but to be free from both the sash and the sash casing.

A further object of this invention is to provide an anti-rattler that can be easily and cheaply made of but two integral parts and finished such that two or more can readily be carried in the pocket where they can be found whenever occasion arises to use them, such as would be the case with traveling salesmen who are obliged to occupy a different variety of rooms on their various routes, each room perhaps having a window to which this type of antirattler could be readily attached.

A still further object of this invention is to provide a window sash antirattler that will readily engage either side of the sash and when removed, the window will show no signs of having an anti-rattler applied thereto.

With these and many other objects in view which will be more readily apparent as the nature of the invention is better understood, the same consists in the novel construction, combination, and arrangement of parts as will be hereinafter fully pointed out, illustrated and claimed.

It will be quite readily understood by those skilled in the art to which this invention belongs, that the same is quite susceptible to various changes and modifications without departing from the spirit or scope of the invention, but a preferred and thoroughly practical device is shown in the accompanying drawings in which—

Fig. 1 shows a window sash positioned in the casing and having applied thereto a plurality of my improved sash anti-rattler.

It will be readily seen that one of these anti-rattlers is constructed right hand while the other is constructed the reverse, or left hand. This construction is obviously necessary to avoid placing the anti-rattler upside down, in which case the locking member would necessarily be pushed up instead of being pushed down as is the most convenient practice.

Fig. 2 shows the side elevational view of the reverse construction or the left hand anti-rattler, as shown positioned between the sash and casing in Fig. 1 of the drawings.

Fig. 3 is a plan view of the parts shown in Fig. 2 of the drawings.

Fig. 4 shows a cross sectioned view of a portion of a window sash and casing having one of my antirattlers applied thereto.

Fig. 5 is a plan view of the locking member which is shown in assembled position in Fig. 2 of the drawings.

Fig. 6 shows the elevational view of the parts shown in Fig. 5 of the drawings.

Fig. 7 shows the plan and edge views of the base plate adapted to hold the locking member previously pointed out.

Fig. 8 shows a sectional view taken on the line 8-8 in Fig. 2, and is illustrative of the manner of rotatively attaching the locking member to the plate or base member. This construction obviously avoids the use of any rivets that will scratch or otherwise mar the finish on the window sash.

Similar reference numerals refer to similar parts throughout the several figures of the drawings.

In carrying out this invention it is my primary thought to construct an anti-rattler that consists of a minimum number of parts and one that can be used on the most delicate varnished surfaces without in the least way showing any signs of it having been applied, and to this end the present invention consists of but two parts, viz: the stationary part designated by the numeral 10 and the movable part 11, which is also the locking member. The stationary part 10, which forms the base plate to which the locking member 11 is attached is provided with two very important facilities, viz: the pressed cone shaped rivet receptacle designated by the numeral 12, and the locking member stop 13, which is formed by offsetting the base plate slightly and turning a portion of the end back on itself as shown in Fig. 7 of the drawings.

The locking member 11 is provided with an integral locking pin 15, at the base of which an annular recess 16 is provided, into which the frustum of the cone 12 is adapted to be positioned, as shown in Fig. 8 of the drawings. The pin 15 having been placed in position as above indicated, the end 17 is riveted over in alignment with the bottom surface 18 of the base plate. This construction avoids the use of rivets which frequently damage delicate surfaces and are thus objectionable. The locking member is provided with a tapered surface 19 on the casing engaging portion of the locking element. This taper is constructed with a slight angle which also avoids injury to the window casing when applied.

Having thus described my invention what I claim and desire to be secured by Letters 20 Patent is—

1. In combination with a window sash anti-rattler, a base plate, one end of which is straight and of a relatively thin section, while the opposite end is constructed with a 25 reduced width, offset and rolled back upon itself, a cone shaped depression in the straight section resembling the frustum of a cone in which a perforation is made and

a locking member having an integral projecting pin adapted to coact with the cone shaped depression in the base plate and rotatively secured thereto.

2. In combination with an antirattler, a base plate having a cone shaped perforation therein, a locking member having an integral projecting pin thereon, an annular groove concentric with, and at the base of the pin, a tapered point at one end of the locking member and an offset lever adapted to be engaged with the thumb at the opposite end.

3. In an antirattler for windows and like fixtures, a base plate, a locking member, integral means for attaching the locking member to the base plate, an integral projecting rivet, projecting from the face of the locking member means for rotatively assembling the locking member with the base member, a stop on the base member and an offset handle on the locking member adapted to engage the stop when locked in position on the window.

In testimony whereof I affix my signature.

WILLIAM I. STINE.
